UNITED STATES PATENT OFFICE.

CLARK D. SPALDING, OF BALTIMORE, MARYLAND.

SHUTTER.

SPECIFICATION forming part of Letters Patent No. 760,764, dated May 24, 1904.

Application filed February 23, 1904. Serial No. 194,944. (No model.)

To all whom it may concern:

Be it known that I, CLARK D. SPALDING, of Baltimore, Maryland, have invented a new and useful Improvement in Shutters, which invention is fully set forth in the following specification.

In so-called "modern" fireproof buildings the window-openings are the vulnerable points at which fires on the exterior gain access to the combustible woodwork, fittings, furniture, and the like within. Fireproof shutters heretofore devised for closing such openings are seldom used principally for the reasons, it is believed, that those which open on the outside objectionably deface the building and those which roll up in recesses contiguous to the window are objectionably expensive and not readily and easily operable.

With the object of overcoming these difficulties and attaining other advantages my invention relates to fireproof or fire-resisting shutters adapted under ordinary conditions to be freely moved back into recesses in the wall of the building at the sides of the window-opening. Means are provided to cause said shutters when closed to form a tight joint with the outer edges of the slots at the sides of the window-opening and when the shutters are opened to tightly close the slots through which they slide into the recesses, thereby excluding rain, snow, dust, &c., and giving a neat finish to the edge of the window-opening.

Other important features of the invention will be referred to in describing the invention in connection with the accompanying drawings, in which—

Figure 1 is an outside elevation of a part of the wall of a building, showing a window-opening to which my invention is applied. Fig. 2 is a transverse sectional view of Fig. 1. Fig. 3 is a detail sectional view on line 3 of Fig. 2. Fig. 4 is an enlarged sectional view showing the means for effecting a tight joint at the outer edge of the slot when the shutter is closed. Fig. 5 is a sectional detail view showing the manner of closing the slot when the shutter is open. Fig. 6 is a detail perspective of part of the outer edge of the shutter, showing a ring or loop adapted to be gripped in closing the shutter. Fig. 7 is a

perspective view of the metallic frame which extends up the sides and across the top of the window-opening. Fig. 8 is a detail perspective showing one of the shutter-supporting rollers and its rail. Fig. 9 is a detail perspective showing the catch for holding the shutters tightly together when closed. Fig. 10 is a view similar to Fig. 2, showing a modified structure. Fig. 11 is a detail of the right-hand shutter of Fig. 10, and Fig. 12 is a detail of a turn-button shown in Fig. 10.

2 is the stone sill of a window-opening inclined outward from the windows, as shown in Fig. 3, to give a fall for draining off water. At its extreme ends, however, the upper face 65 of the sill is not inclined, thereby forming a ridge 3 across each end under the projecting and overhanging edge of the wall, thereby preventing water (in the case of a driving rain, for example) from finding its way beyond the ends of the sill and into the recesses and wall. The inner edges of ridges 3 are dished or curved down to the inclined surface of the sill, as shown at 4, Fig. 1.

5 are recesses or chambers in the wall 75 along the sides of the window-opening adapted to receive the shutters when the latter are opened. The width of these recesses is such as to permit the slight lateral movement of the shutters, referred to hereinafter. A much 80 shallower recess 6 (see dotted lines, Fig. 1) extends across the top of the window-opening to provide space in which the rollers 7 on the shutters run on a rail 8.

9 is a metallic frame (see Fig. 7) resting at 85 its lower ends upon sill 2 near the ridges 3 (see Fig. 1) and extending up both sides and across the top of the window-opening. Said frame is secured in any suitable manner to the wall.

10 10 are slots extending up the sides of frame 9 and part way across the top, through or in which slots the shutters 11 11 move into and out of the recesses or chambers 5 5 and 6.

At the sides of the frame 9 the slots 10 are 95 countersunk—that is to say, they are through a depressed part of the frame—forming inclined shoulders 12 12. Webs 13, 14, and 15, Fig. 7, connect the two parts of the frame 9, which would otherwise be severed by the slots. 100

Across the outer edge of each shutter is a flange 16, having inclined edges. The horn 17 of a cam-lever 18, pivoted to the inside of one shutter, works through slots 19, Fig. 9, in flanges 16 to engage a pin 20 on the other shutter, and thereby tightly clamp the meeting edges of the shutters (the flanges 16 16) tightly together when the latter are closed. The cam-lever and pin are of such dimensions 10 as to readily pass through slots 10 when the shutters are opened.

Referring to Fig. 4, 21 is an arm located in a pocket 22 in the wall, having at one end a head 23, which fits into a recess in the inner 15 face of the frame 9, and at its other end a foot 24, having an inclined edge. A screw 25 rigidly secures the arm to the frame. When the shutter is closed to its full extent, the inclined edge of the foot bears against a knob or 20 projection 26 on the shutter, forcing the latter outwardly and causing it to bear tightly against the outer edge of slot 10, and thus form a tight joint, preventing fire, rain, or the like from entering recess 5 when the shutter 25 is closed. As shown in Fig. 1, there are four sets of arms 21 and knobs 26, two sets for each shutter. To allow for this lateral movement of the shutters, each roller 7 and the 30 space between the arms of its hanger 27 are wider than the rail 8. By extending down on opposite sides of the rail to the door the arms of the hanger prevent disengagement of the roller and rail.

When the shutters are opened, the flanges 35 16 fit into the countersink of the slots 10 10, closing the latter to exclude rain, dust, &c., and giving a neat flush finish to the inner edge of the window-opening, Fig. 5. The inclined edges of the flanges 16 by contacting with the 40 inclined shoulders 12 properly center the shutters in the slots and form tight joints.

The fireproof or fire-resisting shutters may be made of sheet metal, as shown in Figs. 1 to 4, of wood covered with thin sheet metal, 45 as shown in Figs. 5 and 6, or in any other suitable way.

In Fig. 6 I have shown a loop or eye 28 projecting into a semispherical cavity in the edge of the shutter and adapted to be engaged 50 by one or more fingers to pull the shutter out of its recess when it is desired to close the same.

The above description applies to the modified construction shown in Fig. 10 with the following exceptions: The left-hand shutter 30 has no flange at its outer edge; but the slot 10, through which it moves, is adapted to be closed (when the shutter is opened) by the cover 31, hinged to frame 9 at 32, and adapted to be 55 secured in its closed position by a turn-button 33, Fig. 12.

35 is a flange hinged at 36, Figs. 10 and 11, to the outer edge of the right-hand shutter 34, adapted to be turned to the position shown in 60 dotted lines, Fig. 10, and close slot 10 when

the shutter is open or to be turned to the position shown in full lines and lap the joint between the shutters when the latter are closed.

As will be apparent, the cover 31 at the left of Fig. 10 could be dispensed with and shutter 30 also provided with a hinged flange similar to 35, but adapted to swing inwardly and lap the joint on the inside when the shutters are closed. Likewise both shutters could be without a flange, and two doors 31 provided 75 for closing the slots 10 at the opposite sides of the window-opening.

40, Figs. 2 and 10, is the usual window-frame, in which lower and upper windows 41 and 42 are adapted to slide. 80

While I have illustrated and described preferred embodiments, it is to be understood that extensive modifications and changes may be made without departing from the nature and principle of the invention. Likewise 85 some of the novel features may be omitted while still employing others. For example, other equivalent means may be substituted for the arms 21 and knobs 26. While the slots 10, leading into the recess 5, are preferably formed in frame 9, said frame may be entirely omitted, the slots in that event being the outer open 90 ends of the recesses. The transverse dimensions of the recesses may be the same as those of the slots. 95

While I have referred particularly to the use of the shutters for closing window-openings outside of the windows, they may be also employed for closing door-openings outside of the combustible doors ordinarily used. 100 Furthermore, only one shutter may be employed, as in the case of narrow openings.

What I claim as new is—

1. The combination with the wall of a building having a window or analogous opening therethrough, a recess or chamber extending laterally into said wall from the edge of said opening, means for closing the opening under ordinary conditions, and a fireproof or fire-resisting shutter adapted to move into and out of said recess to open and close said opening outside of the ordinary closing means. 105

2. The combination with the wall of a building having a window or analogous opening therethrough, a recess or chamber extending back into said wall from the edge of said opening, a shutter adapted to move freely into and out of said recess, and means for closing the slot leading into said recess when the shutter is open. 110

3. The combination with the wall of a building having a window or analogous opening therethrough, a recess or chamber extending back into said wall from the edge of said opening, a shutter adapted to move freely into and out of said recess, and means on the shutter for closing the slot leading into said recess when the shutter is open. 115

4. The combination with the wall of a building having a window or analogous opening 120

- therethrough, a recess or chamber extending back into said wall from the edge of said opening, a shutter adapted to move freely into and out of said recess, and a flange on the shutter 5 for closing the slot leading into said recess when the shutter is open.
5. The combination with the wall of a building having a window or analogous opening therethrough, a recess or chamber extending 10 back into said wall from the edge of said opening, a shutter adapted to move freely into and out of said recess, and a flange projecting on opposite sides of the shutter for closing the slot leading into said recess when the 15 shutter is open.
6. The combination with the wall of a building having a window or analogous opening therethrough, a recess or chamber extending back into said wall from the edge of said 20 opening, a shutter adapted to move freely into and out of said recess, and a flange across the outer edge of the shutter closing the slot leading into said recess when the shutter is open.
7. The combination with the wall of a building having a window or analogous opening 25 therethrough, a shutter adapted to move freely through a slot at the edge of the window-opening, and means for closing said slot when the shutter is open.
- 30 8. The combination with the wall of a building having a window or analogous opening therethrough, a shutter adapted to move freely through a countersunk slot at the edge of the window-opening, and closing means fitting into the countersink and extending 35 across the slot to close the same when the shutter is open.
9. The combination with the wall of a building having a window or analogous opening 40 therethrough, a shutter adapted to move freely through a countersunk slot at the edge of the window-opening, and means forcing said shutter against the outer edge of the slot to form a tight joint when the shutter is closed.
- 45 10. The combination with the wall of a building having a window or analogous opening therethrough, a shutter adapted to move freely through a countersunk slot at the edge of the window-opening, and a fixed inclined

surface acting against a projection on the 50 shutter to force the latter against the outer edge of the slot to form a tight joint when the shutter is closed.

11. The combination with the wall of a building having a window or analogous opening 55 therethrough, a recess or chamber extending back into said wall at the edge of the recess, and means forcing said shutter against the outer edge of the slot at the open end of the recess to form a tight joint when the shutter is closed.

12. The combination with the wall of a building having a window or analogous opening therethrough, a recess or chamber extending back into said wall at the edge of the 65 recess, a projection on the shutter near its inner end, and a fixed inclined surface in the recess near its open end acting against said projection to force the shutter against the edge of the slot at the open end of the recess to 70 form a tight joint when the shutter is closed.

13. The combination with the wall of a building having a window or analogous opening therethrough, a recess or chamber extending back into said wall at the edge of the 75 opening, a metallic plate extending along the edge of the opening and having a slot therethrough leading into the recess, and a shutter adapted to move into and out of said recess through said slot.

14. The combination with the wall of a building having a window or analogous opening therethrough, a recess or chamber extending back into said wall at the edge of the opening, a metallic plate extending along the 85 edge of the opening and having a countersunk slot therethrough leading into the recess, a shutter adapted to move into and out of said recess through said slot, and a flange on the cover adapted to fit into said countersink 90 across the slot when the shutter is open.

In testimony whereof I have signed this specification in the presence of two subscribing witnesses.

CLARK D. SPALDING.
